GEORG SEIBT, OF BERLIN-SCHONEBERG, GERMANY

ELECTROSTATIC LOUD-SPEAKER

Application filed August 8, 1927, Serial No. 211,544, and in Germany August 12, 1926.

This invention relates to a loud speaker operating on the electrostatic principle. Its main characteristic consists in the fact that those surfaces or surface elements which are set in oscillation by the electromechanical forces, and which emit the sound into the surrounding space, are arranged in a manner which is particularly advantageous for the radiation of sound.

10 According to the invention the arrangement is such that the propagation of sound can take place in as many different directions as may be desired. This is attained by constructing the fixed electrode in the form of a prism, the outer faces of which are wholly or partly covered by the vibrating coverings.

In order not to damp the vibrations of the diaphragm more than is necessary the prism is preferably made hollow and the faces covered by the diaphragm are perforated in a manner known in itself, these perforations preventing an excessive air-cushioning effect between the diaphragm and the fixed electrode.

25 The number of sides of the prism may be as large as may be desired. Prisms of hexagonal or quadrilateral shape are advantageous. In the latter case the prism may assume the special form of a cube.

30 The invention is illustrated by way of example in the accompanying drawings, wherein:

Figures 1 and 2 show in cross section and in plan respectively one particularly advantageous form of the invention;

Figure 3 is a plan and Figure 4 a corresponding sectional elevation of another constructional form of the invention; and

Figure 5 shows an outer covering of the loud speaker illustrated in Figures 1 and 2.

In the constructional form illustrated in Figures 1 and 2, a brass cylinder *s*, having an external diameter of about 100 millimeters, a wall thickness of from 3 to 5 millimeters and a height of 200 millimeters, is milled off on the outer periphery in such a manner that a regular hexagon is produced. The wall of the prism is provided at numerous points with perforations *h*. On grounds of convenience in manufacture it is however

advisable to mill, plane or turn channels or grooves in the brass body. If the grooves are planed they will run in the longitudinal direction of the prism. If they are turned they will run circumferentially round the periphery.

Now round the periphery of the prism is placed a suitable diaphragm *M* of indiarubber, celluloid or oiled paper. That side of the diaphragm which is rendered conductive (1), by coating it with colloidal graphite ("aquadag"), for example, is on the outside, if the prism itself is not insulated on the external periphery.

If such insulating is carried out however, for example by coating it with a layer of varnish, a metallic diaphragm, of aluminium foil for example can be used, or the layer of aquadag on the celluloid diaphragm may be turned inwards. In this way the great advantage of smaller air gaps is obtained. The diaphragm is only to bear on the edges of the prism and elsewhere is to be separated by a definite air gap from the metallic body, which may be about 0.03 millimetres at the centre of the sides. In order to secure this air gap, the sides of the polygon are not exactly rectilinear, but are slightly concave in the centre, as shown on an exaggerated scale at *a*. The departure from the straight should amount to about 0.05 millimetres at the centre, and decrease uniformly towards the edges of the polygon.

Now if the diaphragm operates under a direct current voltage, it deflects somewhat, by about 0.02 millimetres at the centre of the sides of the polygon, so that there still remains there a working distance of 0.03 millimetres.

It is not advisable to select for the diaphragm a single large coherent surface, since in such a case a uniform bearing on the edges of the prism is not ensured, and the air gaps at those positions where the diaphragm is intended to vibrate are by no means uniform; for it must be observed that differences in distance of a few hundredths of a millimetre already produce a considerable effect, as the distance of the diaphragm from the cylinder at those points where it has to vibrate is regularly on an average only a few hun-

dredths of a millimetre, for example 0.03 millimetre.

Irregularities in the air gap make themselves felt by a diminution in the sensitivity.

On these grounds the diaphragm is divided into bands or strips which are passed round the periphery of the cylinder and are connected by their ends with one another or with the cylinder. Fig. 2 shows three bands 10 of celluloid for example, the ends of which are connected with two small metallic pieces *m m*, which in their turn are screwed together. By turning the screw to a greater or less extent 15 the pull of the band can be adjusted, which is of importance for the purpose of bringing out the utmost sensitivity of the loud speaker.

Instead of bands or strips, thin threads 20 which have been rendered conductive, silk threads for example, may be employed, which have been drawn through aquadag. These threads are wound onto the cylinder thread by thread, so that as regards sound emission, 25 they act exactly like a coherent layer. Of course in such a case the surface of the cylinder or prism must be provided with a coating of varnish in order to prevent short circuits. The sort of varnish which is employed 30 for the so-called varnish wires known in electrical technology is quite suitable.

The silk threads may alternatively be replaced by thin copper or aluminium wires insulated with varnish or silk braiding.

35 One great practical advantage of the loud speaker described consists in the comparatively shall amount of room it takes up as compared with the statophones with a single large diaphragm.

40 Obviously the two end faces of the prism may also be covered by the vibrating coverings. For the sake of greater clearness this case is not illustrated in Figures 1 and 2. The covering of all the surfaces with diaphragms comes into consideration more particularly when the prism is of quadrilateral cross section and its height is equal to the length of its sides, that is, when the fixed 45 electrode is of cubical form.

50 The prism forming the fixed electrode may alternatively consist of a very large number of side faces, and in the limit may even be a cylinder. In the latter case it is not the cylinder surface but the base and top surfaces 55 that are covered with the vibrating diaphragms. Such a constructional form is shown in Figures 3 and 4.

Figs. 3 and 4 illustrate one constructional example, Fig. 3 being a plan, and Fig. 4 a 60 corresponding sectional elevation. In these two figures *S S* are two circular pieces of metal, which are provided with numerous holes of from 1 to 2 millimetres in diameter.

The two pieces may be soldered together or 65 otherwise connected together at *c*. *r r* are

rings of insulating material about 5 millimetres wide and 0.05 millimetre thick. *M*₁ 70 *M*₂ are two diaphragms which are lightly stressed at the periphery in a convenient manner. As a material for the diaphragms indiarubber is suitable, which, on the side remote from the metallic pieces *S S* is rendered conducting by coating it with graphite. The intermediate rings *r r* may be stuck onto the metallic pieces, and the diaphragms 75 onto the rings with adhesive. Since the diaphragms deflect most at the centre, it is advantageous not to turn the metallic pieces *S S*, exactly plane, but to curve the surfaces slightly, in order that the diaphragms 80 may not bear against them in the centre. Instead of indiarubber, celluloid or some other material which is rendered conducting on one side may be employed for the diaphragm. If metal such as aluminium is 85 used for the diaphragm, it is advisable to varnish the pieces *S S* on the surface or to coat them with paper, care being taken that the perforations are not left closed up. Paper readily admits of being subsequently pierced 90 with a needle.

The metal pieces *S S* form one coating, and the two diaphragms the other coating of the condenser loud speaker. The arrangement of the electrical connections and the method 95 of operation do not in any way differ from those which are usual with other electrostatic loud speakers.

Fig. 5 illustrates an outer covering of the cylinder loud speaker according to Figs. 1 100 and 2, and is intended to show the possibility of an artistic design.

Thus for example the fixed counter-electrode might be constructed as an elongated prism of triangular cross section, as indicated in Figs. 9 and 10.

What I claim is:—

1. An electrostatic loud speaker, comprising a fixed prism, and vibrating coverings covering the external faces of said fixed 110 prism.

2. An electrostatic loud speaker, comprising a fixed hollow prism, said hollow prism being formed with perforations in its faces, and vibrating coverings covering externally 115 the perforated faces of said fixed prism.

3. An electrostatic loud speaker, comprising a fixed prism with its faces made somewhat concave, and vibrating coverings covering the external faces of said fixed prism, 120 the vibrating coverings being electrically insulated from the fixed prism where they bear upon said fixed prism.

4. An electrostatic loud speaker, comprising a fixed prism, and vibrating coverings 125 covering the external faces of said fixed prism, said vibrating coverings being made of insulating material and rendered conductive on their external surfaces.

5. An electrostatic loud speaker, compris- 130

ing a fixed prism, and vibrating coverings covering the external faces of said fixed prism, said vibrating coverings consisting of strips passed round the peripheral surface 5 of the prism.

6. A method of manufacturing an electrostatic loud speaker, comprising milling flats on a cylinder to produce a fixed prism, and covering the external faces of the fixed prism 10 so produced with vibrating coverings.

7. An electrostatic loud speaker, comprising a fixed prism, and vibrating coverings covering the external faces of said fixed prism, said vibrating coverings being made 15 of insulating material and rendered conductive on their external surfaces, and said insulating coverings being in contact with said fixed prism.

In testimony whereof I have signed my 20 name to this specification.

GEORG SEIBT.
